Primary Examiner — Mojtaba Tehrani

(57) **CLAIM**

The ornamental design for a wireless earphone, as shown and described.

DESCRIPTION

1. Wireless earphone

1.1 : Perspective

1.2 : Front

1.3 : Back

1.4 : Left

1.5 : Right

1.6 : Top

1.7 : Bottom

The present design has a long and flat shape so as to be stored in an earphone storage part of a smart phone. The evenly broken lines disclose unclaimed subject matter, which form no part of the claimed design. Figure 1.1 is a view showing the whole shape of the present design; figure 1.2 is a front view thereof; figure 1.3 is a rear view thereof; figure 1.4 is a left side view thereof; figure 1.5 is a right side view thereof; and figure 1.6 is a plan view thereof; figure 1.7 is a bottom view thereof.

1 Claim, 7 Drawing Sheets
